US0D1000978S

(12) **United States Design Patent** (10) Patent No.: **US D1,000,978 S**
(45) Date of Patent: ** *Oct. 10, 2023

(54) **LIDAR**

(71) Applicant: **HESAI TECHNOLOGY CO., LTD.**,
Shanghai (CN)

(72) Inventors: **Shiyu Zhao**, Shanghai (CN);
Hongguang Wang, Shanghai (CN);
Shaoqing Xiang, Shanghai (CN)

(73) Assignee: **HESAI TECHNOLOGY CO., LTD.**,
Shanghai (CN)

(*) Notice: This patent is subject to a terminal disclaimer.

(**) Term: **15 Years**

(21) Appl. No.: **29/754,461**

(22) Filed: **Oct. 12, 2020**

(30) **Foreign Application Priority Data**

Apr. 23, 2020 (CN) 202030172215.8

(51) LOC (14) Cl. **10-04**

(57) **CLAIM**

The ornamental design for a lidar, as shown and described.

DESCRIPTION

FIG. 1 is a front view of a lidar showing my new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a front perspective view thereof.

The broken lines depict portions of the article that form no part of the claimed design.

1 Claim, 7 Drawing Sheets
